UNITED STATES PATENT OFFICE.

ELWOOD C. PHILLIPS, OF CHICAGO, ILLINOIS, ASSIGNOR TO GILBERT H. HOXIE, OF SAME PLACE.

DESIGN FOR A HAND-RIPPER.

SPECIFICATION forming part of Design No. 31,175, dated July 11, 1899.

Application filed June 5, 1899. Serial No. 719,493. Term of patent 7 years.

To all whom it may concern:

Be it known that I, ELWOOD C. PHILLIPS, a citizen of the United States, residing at Chicago, in the county of Cook and State of Illinois, have invented and produced a new and original Design for Hand-Rippers; and I do declare the following to be a full, clear, and exact description of the same, reference being had to the accompanying drawings, forming a part of this specification, and in which—

Figure 1 is a perspective view of the hand-ripper, and Fig. 2 an enlarged transverse section through the ripper-knife and the shield thereof.

The present invention relates to a design for a hand-ripper for domestic and like uses in ripping seams of clothing and other wearing-apparel; and the said invention consists in the structural configuration hereinafter described, and illustrated in the accompanying drawings.

The present ripper comprises a handle portion 1, by which the implement is grasped and held by the user, and having a form adapted

to afford a convenient grip for the hand of 25 such user, as shown. Extending from the handle is the knife-blade 2, of a flat straight formation, as shown, and which blade, except a small portion of its cutting edge, is inclosed within a knife-shield 3, that has a substantially triangular form in cross-section, with the knife-blade projecting through the same at one of the apexes of the triangle, as shown.

The essential feature of the present invention is the knife-blade having a flat formation 35 and a triangular-shaped shield inclosing said knife, with the cutting edge of the knife projecting through such shield at an angular corner thereof.

I claim—

The design for a hand-ripper, substantially as herein shown and described.

In testimony whereof witness my hand this 1st day of June, 1899.

ELWOOD C. PHILLIPS.

In presence of—

ROBERT BURNS,
M. H. HOLMES.
